H. F. GURNEY & W. M. CUMMISKEY.
ELECTRIC ELEVATOR.
APPLICATION FILED FEB. 26, 1908.

909,889.

Patented Jan. 19, 1909.

UNITED STATES PATENT OFFICE.

HOWARD F. GURNEY, OF JERSEY CITY, NEW JERSEY, AND WILLIAM M. CUMMISKEY, OF HONESDALE, PENNSYLVANIA; SAID CUMMISKEY ASSIGNOR TO SAID GURNEY.

ELECTRIC ELEVATOR.

No. 809,639.

Specification of Letters Patent.

Patented Jan. 19, 1909.

Application filed February 26, 1908. Serial No. 417,932.

To all whom it may concern:

Be it known that we, HOWARD F. GURNEY and WILLIAM M. CUMMISKEY, citizens of the United States, and residents, respectively, of Jersey City, in the county of Hudson and State of New Jersey, and of Honesdale, in the county of Wayne, State of Pennsylvania, United States of America, have invented certain new and useful Improvements in Electric Elevators, of which the following is a specification.

Our invention relates to improvements in electric elevators and particularly to a novel connection of the electrical circuits used in the controllers for such apparatus, and its object is to increase the safety and efficiency of installations of this character.

We will describe our invention in the following specification and point out the novel features thereof in claims.

The drawing is a diagrammatic representation of certain portions of an elevator apparatus and associated parts together with certain connected electrical circuits which are used in carrying out our invention. In this drawing + and — designate mains from a suitable source of electrical supply which, after passing through a main-line switch 10, run to various parts of the apparatus 30 through circuits which will be pointed out hereinafter.

20 is a starting switch which comprises a plurality of stationary contacts 21, 22, 23, 24, 25 and 26 and two movable contact plates 27 and 28. The latter are mounted upon but insulated from a vertically movable rod 29 which is connected with the core 31 of an electromagnet or solenoid 30 by means of a rod 33. 32 designates the winding of this solenoid.

34 is a piston affixed to the connecting rod 33. 35 is a closed cylinder surrounding this piston and arranged to form an air-cushion or dash-pot for controlling the rapidity of movement of the piston 34 and its connected parts in both directions.

40 is a reversing switch which comprises stationary contacts 41, 42, 43, 44, 45, 46, 47 and 48 and movable contact plates 49, and 50 mounted upon but insulated from a vertical rod 51 which is directly above the rod 29. A pendant 52 is pivoted to the lower end of the rod 51 and is normally in alinement with the rod 29. It is provided with a slot 53 into which a pin 54 projects. This pin is on

a rod 55, one end of which is attached to the core 56 of a solenoid, the winding of which is designated by the numeral 57. The other end of rod 55 supports an insulated contact plate 58 which is pressed against two stationary contacts 60 and 61, by means of a spring 59. Whenever solenoid winding 57 is energized the contact plate 58 will be drawn back against stationary contacts 62 and 63 and at the same time the pendant 52 will be drawn back into the position shown in dotted lines and out of the path of movement of the rod 29.

64 designates the armature of an electric motor which, in any of the well-known manners, is arranged to drive a hoisting mechanism and a car. The armature terminals of this motor are connected by conductors 65 and 66 with stationary contacts 42 and 44, respectively. The terminals of the shunt field 67 of this armature are connected by conductors 68 and 69 with stationary contacts 25 and 24, respectively.

Below the solenoid 30 a brake 70 is shown. This comprises a brake-pulley 71 and a pair of brake-shoes 72 mounted upon pivoted levers 73, the upper ends of which are connected together and to a rod 36 by means of a pair of toggle-levers 37. The rod 36 is affixed to the solenoid core 31 and the parts are so arranged that when the solenoid 30 is energized and the core 31 raised thereby the pivoted levers 73 will be pushed apart and the brake-shoes released thereby. When the solenoid is deenergized the weight of its core and its connected parts will force the pivoted levers 73 together and thereby apply the brake-shoes to the pulley 71 which is connected to some movable part of the elevator hoisting mechanism. The brake is therefore actuated by the solenoid which also actuated the starting switch.

74, 75 are contact plates mounted upon the brake-levers 73, and 76, 77, 78, 79 are stationary contacts with which these contact plates coat.

80 is an automatic rheostat which is arranged to gradually cut a resistance 81 out of the motor armature circuit. This rheostat comprises a pair of brushes 82 which bear upon and make contact with a metallic strip 83 and a plurality of stationary contacts 84. The resistance 81 is connected to each one of the latter so that when the brushes 82 are moved up over the stationary

contacts, the resistance is cut out in a plurality of steps. The brushes 82 are mounted upon a vertical rod 85 which depends from the core 86 of a solenoid, the winding of which is designated by 87. A piston 88 is attached to one end of the rod 85. This piston is within a closed cylinder 89 which may be filled with oil or other fluid and is arranged to retard the upward movement of the brushes 82. A valve in the piston 88 allows the piston and its connected parts to move freely downward.

90 designates an elevator-car within which is a manually operated switch 91 which comprises a pivoted lever 92 and two stationary contacts 93 and 94. This lever may be moved into engagement with either one or the other of these contacts.

The above description is of the various parts of the apparatus which are connected together by a wiring system made up of a plurality of circuits which will now be traced and the operation of our invention described.

25 The main-line conductors + and - are connected by means of conductors 11 and 12 with stationary contacts 22 and 26. A conductor 12^A is run from the + main to the pivoted lever 92 of the car-switch. If 30 this car-switch lever is moved to the left onto contact 93, a circuit will be closed through the conductor 95, contacts 60, 61, which are bridged by plate 58, conductor 38, winding 32 of solenoid 30, and conductors 35 39 and 11 to the negative main. This solenoid 30 will be energized and will raise its core. This will cause plates 27 and 28 to be moved up against contacts 21, 22 and 25, 26, respectively, to thereby connect the motor 40 shunt field across the line, and to also close a circuit between the motor armature and the mains through the resistance 81. This operation will also actuate the reversing switch 40 to cause the current to pass 45 through the armature in the desired direction. This forms no part of the present invention, and as it is fully set forth and described in Patent Number 851,933 issued to one of applicants April 30th, 1907, a specific 50 description of its operation is not deemed necessary. The core 31 will at the same time release the brake 70. The effect of these operations will be to cause the motor to run slowly in one direction and the car 55 90 to be driven thereby.

When the brake-shoes have been moved away from the brake-pulley, the contact plates 74 and 75 will be moved back against stationary contacts 76, 77 and 78, 79, respectively. This will cause a circuit to be closed from the + main through the car-switch, to and through conductor 97, solenoid winding 87, conductors 87^A, 76^A, 79^A, 39 and 11 to the negative or - main. The solenoid core 86 65 will then be raised and the resistance 81 grad-

ually cut out of the motor armature circuit under the action of the dash-pot 89. It is to be noted that this part of the operation cannot take place until the brake has been actuated and released.

70 The motor and car will continue to run in one direction until the circuit through solenoid windings 32 and 87 is broken, either by some of the automatic arrangements usually employed with apparatus of this kind, 75 or by the operator in the car bringing the car-switch back to its central position. This will cause the current to be cut off from the motor and the brake to be applied. At the same time the brushes 82 will drop and will 80 thereby quickly connect a part of the resistance 81 in series with the motor armature. If the operator throws pivoted lever 92 of the car-switch to the right against contact 94, the operation will be similar to that 85 above described, except that in this case the solenoid winding 57 will be energized and the reversing switch 40 will cause the current to pass through the motor armature in the opposite direction so that the rotation of 90 the motor and the movement of the car will be in the opposite direction to that before mentioned.

We usually employ a single circuit-closer associated with the brake for controlling the 95 rheostat solenoid circuit, but in the drawing we have shown two of these circuit-closers connected in series as this arrangement may be used if desired so that both brake-shoes must be released before the armature resist- 100 ance can be removed.

The advantages of this invention are obvious. It fully insures the proper rotation of steps in the operation of the controller. It prevents an overload upon the motor 105 which might be caused by making the latter work against an applied brake. It also supplies a time element during which the motor begins its rotation before its series starting resistance is cut out, which time may be augmented by the dash-pot 35.

The various apparatus shown and described are arbitrarily selected to illustrate our invention. They are not a part of the present invention, nor is the general wiring 115 system shown, but our invention may be applied as well to many other forms of apparatus and in conjunction with other systems of wiring.

Instead of connecting the solenoid 87 with 120 the mains through the car-switch, its conductor 97 may be connected with stationary contact 25, and the conductor 79^A connected with the stationary contact 21 so that the closing of the starting switch and the releasing of the brake serve to complete its circuit.

What we claim is.—

1. In an elevator, an electric motor, a starting resistance therefor, an electromag- 130

net for controlling the starting resistance, a circuit for said magnet, a circuit closer for the motor, a brake, an electromagnet for actuating the circuit-closer and releasing the brake, and means for preventing the completion of the circuit of the resistance-controlling magnet while the brake is applied.

2. In an electrically-controlled elevator, an electric motor having an armature, a starting resistance in circuit with the armature, a solenoid for gradually cutting out the starting resistance, a starting switch, a brake, an electroresponsive device for actuating the starting switch and the brake, a switch for controlling said electroresponsive device, and means actuated by the releasing movement of the brake for energizing the starting resistance solenoid.

3. In an electrically-controlled elevator, a car, an electric motor having an armature, a starting resistance in circuit with the armature, a solenoid arranged to cut the starting resistance out of circuit with the motor armature, a dash-pot controlling the action of the solenoid; a motor-starting switch, a brake, a pivoted brake-lever connected therewith, an electroresponsive device for actuating the starting switch and the brake-lever, a manually operated switch in the car for controlling said electroresponsive device, and a circuit-closer connected with the brake-lever arranged to close the resistance-controlling solenoid circuit when the brake-lever has been actuated to release the brake.

35 4. In an electrically-controlled elevator, a car, an electric motor having an armature, a starting resistance in circuit with the armature, a solenoid arranged to cut the starting resistance out of circuit with the motor armature step by step, a dash-pot controlling the action of the solenoid in one direction; a motor-starting switch, a brake, a pivoted

brake-lever connected therewith, an electroresponsive device for actuating the starting switch and the brake-lever, a manually operated switch in the car for controlling said electroresponsive device, and a circuit-closer connected with the brake-lever arranged to close the resistance-controlling solenoid circuit when the brake-lever has been actuated to release the brake and when said car-switch is closed.

5. In an electrically-controlled elevator, a car, an electric motor having an armature, a starting resistance in circuit with the armature, a solenoid arranged to get the starting resistance out of circuit with the motor armature step by step, a dash-pot controlling the action of the solenoid in one direction, a motor-starting switch, a reversing switch and a brake; a solenoid arranged to actuate the starting switch and the brake, a switch in the car for controlling said actuating solenoid, a pair of pivoted brake levers connected with the brake, and a circuit-closer connected with each of the brake levers arranged to close the resistance-controlling solenoid circuit when the brake levers have been actuated to release the brake and when said car switch is closed.

In testimony whereof we have signed our names to this specification in the presence of two subscribing witnesses.
